UNITED STATES PATENT OFFICE.

JASPER EMET HIGDON, OF PEARSALL, TEXAS.

DRILLING MACHINE.

Application filed November 23, 1925. Serial No. 70,902.

This invention contemplates the provision of a drilling machine capable of being moved from place to place with a minimum of effort, and adapted to be operated from the traction wheels of a motor operated vehicle, subsequent to jacking the wheels off the ground, the drilling mechanism as well as the controlling elements of the vehicle being operated by a plurality of levers conveniently located at one end of the machine.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a side elevation of the machine.
Figure 2 is a top plan view.

Figure 3 is a fragmentary end elevation.
Figure 4 is a fragmentary longitudinal sectional view.

Figure 5 is a fragmentary transverse sectional view.

Figure 6 is a detail view of the sand reel.

Figure 7 is an enlarged transverse sectional view showing the manner in which the arched shaped member is mounted for operating the drop beam.

Figure 8 is a detail view showing the manually operable means for rotating the drill reel.

Referring to the drawings in detail, 10 represents the frame of a motor operated truck or vehicle upon which is supported an auxiliary frame like structure indicated generally at 11, the latter supporting the drilling mechanism to be hereinafter described. It might here be stated that this mechanism is operated by the motive power of the vehicle, by jacking the traction wheels off the ground, one of which wheels is indicated at 12, and associated with each wheel is a gear 13. These gears are riveted on the brake drums of the respective wheels.

50 The drilling mechanism includes a sand

reel 14 which is loosely mounted upon a shaft 15, the latter being journalled in suitable bearings on the auxiliary frame 11. This shaft 15 supports at the ends thereof sprocket wheels 16, over each of which and 55 the adjacent gear or sprocket wheel 18 is trained an endless chain 17. After the wheels 12 of the vehicle have been jacked off of the ground, they are supported in this position by means of blocks or other suitable 60 means 18 upon which the frame 10 is adapted to rest. Manifestly, the shaft 15 is rotated from the rear wheels 12 under the motive power of the vehicle, the shaft 15 being connected by gearing 19 with the shaft 20. This 65 latter mentioned shaft is also journalled in suitable bearings on the auxiliary frame 11, being arranged in spaced parallel relation with the shaft 15, and supporting the drill reel 21. Rising from the rear ends of the auxiliary frame 11 is a boom 22 which supports adjacent the upper end thereof spaced superimposed pulleys 23 and 24 respectively. The sand line 25 is adapted to be wound about and unwound from the reel 14, and is 70 trained over the pulley 23 above referred to, while the drill line 26 is adapted to be wound about and unwound from the drill reel 21 and is trained over the pulley 24. It will be noted upon inspection of Figure 1 that the drill line 26 is extended forwardly from the reel 21 and trained over a sliding shaft or pulley 27 mounted on a transverse rod 28 at the forward end of the auxiliary frame 11, which shaft is used to guide the line 26 for a 75 proper winding about the drum as will be readily understood. This drill line is then trained over a small pulley 29 arranged adjacent the free end of the drop beam 30, the latter being pivoted upon the rod 28 above 80 referred to and arranged in a horizontal plane. This beam carries a metallic plate 31 adapted to be engaged by the arched shaped member 52 which is utilized and operated 85 in a manner to be hereinafter described for lowering the drop beam 30.

As above stated, the reels are loosely mounted upon their respective shafts, and each reel is adapted to be clutched to the shaft for rotation therewith when its use 100

is desired. As shown in Figure 5 the reel 14 is provided with a clutch member 32 which is recessed as at 33 to receive the cone shaped projection 34 projecting from one side of 5 the adjacent gear 19, the parts being normally held separated or spaced by a coiled spring 35. Mounted for rotation upon the shaft 15 adjacent one end thereof is a collar 36 having a cam-like projection 37 10 adapted to be received by a notch 36' formed in the bearing 37' whereby the reel is caused to slide upon the shaft into clutching engagement therewith, when the collar 36 is turned in one direction. Extending from this collar 15 is an arm 38, the upper end of which is connected with a rod 39 adapted to be operated by a lever 40 arranged at one end of the machine. This operates a brake for retarding the rotation of the adjacent drum. The 20 cam shaped projection 37 is normally received by a notch in the adjacent bearing 37' and the parts arranged as shown in Figure 5. The drill reel 21 is also formed with a clutch engaging member 41 which is recessed as at 25 42 to receive the cone shaped projection 43 forming part of the adjacent gear 19 which parts are normally held separated by a spring 44. Also mounted for rotation upon the shaft 20 at the other end of the reel is a collar 45 having a cam shaped projection 46, the latter being normally received by a notch formed in a stationary collar 47. Carried by the collar 45 is an arm 48, which arm is connected with a rod 49 adapted to be operated 30 by a clutch controlled lever 50 arranged adjacent the lever 40, above referred to. Manifestly, when the collar 45 is rotated on the shaft 20, the cam-like projection 46 cooperates with the stationary collar 47 to 35 force the reel 21 longitudinally of the shaft 20 into clutching engagement therewith. Either of the reels can be put into use by selectively operating the levers 40 and 50 above referred to.

45 Carried by the ends of the shaft 20 are crank arms 51, and pivoted on these arms is the arched shaped member 52 utilized to lower the drop beam 30 intermittently during the operation of the drilling mechanism.

50 The arms 51 are provided with projections 53 which are adapted to be received by similarly shaped notches 54 formed on a collar 55 fixed on the shaft 20, so that the arms 51 rotate with the shaft 20. The arched 55 shaped member 52 possesses the desired degree of resiliency, to hold the crank arms 51 engaged with the collars 55 for the purpose just mentioned, the arms however, being mounted for sliding movement on the shaft 60 20, so that they can be separated from the collars 55 when it is desired to render the crank arms 51 and the adjacent arched shaped member 52 inactive. For this purpose, I make use of a sleeve 56, there being 65 one of these sleeves arranged between each

arm 51 and the adjacent side of the auxiliary frame 11, and mounted to slide upon the adjacent collar 55. Each sleeve 56 is controlled by an arm 57 which is mounted to turn upon the shaft 20, between the said sleeve 56 and 70 the adjacent side of the frame 11, the arm being provided with a cam like projection 58 adapted to be normally received within a notch or recess 59 formed in the frame 11 as shown in Figure 5. The arms 57 at the opposite side of the machine are connected by a rod 60 which in turn is operated by a lever 61 arranged at one end of the machine, both of said arms 57 being actuated at one and the same time. Manifestly, when the 80 arms are turned in one direction, the cam shaped projections 58 move out of their recesses 59, riding against the side of the frame, which of course moves the sleeve 56 outwardly against the crank arms 51 causing 85 the latter to be separated from the collar 55, so that the shaft 20 can rotate without imparting movement to the crank arms 51 for the arched shaped member 52. However, in the normal position of the parts, when the 90 shaft 20 is rotated, the arched shaped member 52 is moved upon its pivots 62 to be drawn to a position over the drop beam 30, and when the arched shaped member is lowered it engages the beam 30, lowering the 95 latter to exert a pull upon the drill cable 25 lifting the drill tool an appreciable distance. During the continued rotation of the shaft 20, the arched shaped member 52 is moved upwardly to release the beam 30 allowing the latter to return to its normal position by the fall of the drill tool from its elevated position as will be readily understood. This operation is continued as long as the machine is in operation and the arched 100 shaped member 52 located to engage the beam 30. It is possible to shift the arched shaped member 52 to an out of the way position thus rendering it inactive, without disengaging the crank arms 51 from the collar 55 105 as above described. For this purpose, the arched shaped member 52 is connected by rod 63 at the opposite sides of the machine, the corresponding extremities of these rods being pivotally connected with vertical lever 110 64 pivoted as at 65 at the opposite sides of the machine. The lower ends of these levers 64 are connected with rod 66 which have their other ends connected by a cross rod 67 which carries a lever 68, so that by operating the 115 latter the arched shaped member 52 can be moved to occupy a position where it cannot be brought into engagement with the drop beam 30. It will be noted upon inspection of Figure 1 that a rod 69 leads from the carburetor of the engine "not shown", so that the same can be regulated or controlled by a lever 70 connected with one end of the rod 69. In other words all of the controlling levers above referred to are arranged at one 120 125 130

end of the machine within convenient reach of the operator so that he may occupy a position to operate the drilling mechanism and at the same time watch the work being done. The drill reel 21 is provided with a braking mechanism including a drum 71 and a brake band 72, the latter being controlled by an operating rod 73, to retard the rotation of the reel 21 as the occasion may require. Also carried by the auxiliary frame 11 and arranged in juxtaposition to the arched shaped member 52 is what I term a bumper 74 which straddles the drop beam 30 and arranged to limit the upward movement of the beam incident to the fall of the drill tool as above described.

It might be desired from time to time to gradually feed more line from the reel 21, which may be accomplished by manually operable means including a shaft 75 having a worm gear 76 adapted to mesh with a gear 77 fixed upon the shaft 20 of the drill reel. The shaft 75 is mounted for sliding movement in its bearings 77', and is equipped with a hand wheel 78 through the instrumentality of which the shaft 75 is controlled. When it is desired to rotate the reel 21 by hand, the shaft 75 is moved toward the gear 77 to cause the worm gear 76 to mesh with the latter. The gear 76 automatically releases itself when the drum 21 starts rotating in a counter-clockwise direction, whereupon the shaft 75 with the gear 76 is moved to the right or forwardly in its bearings, the forward bearing acting as a stop and with which the gear 76 is brought into contact.

The operation of the mechanism is as follows:

The auxiliary frame 11 is of course adapted to be arranged upon an automobile chassis, so that the entire machine can be conveniently moved from place to place, during which the boom 22 lies horizontally upon the frame 11, the boom 22 being pivoted as at 82 to allow it to be swung into this lowered position. When it is desired to use the machine the rear wheels 12 are first jacked off the ground. The motor is then put into operation, and its speed regulated by the lever 70 connected with the carburetor controlled rod 69. Then either the sand line 25 or the drill line 26 can be used, by selectively operating the reels 14 and 21 respectively by means of the clutches above described. When the drill line 26 is being used, the arched shaped member 52 is reciprocated by the crank arms 51 incident to the rotation of the shaft 20, and at the same time is afforded pivotal movement with relation to said arms 51, so as to intermittently engage and lower the drop beam 30, which is subsequently elevated incident to the fall of the drill tool, when the arched shaped member 52 moves away from the beam 30 in its

lowermost position. The return movement of this beam is limited by the bumper 74. The invention in its entirety is very simple in construction, and the parts are so arranged that the attendant occupies a position where he can watch the work being accomplished.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

1. In a machine of the character described, a frame, spaced drums rotatably mounted thereon, cables adapted to be wound about and unwound from said drums, means for independently rotating said drums, a pivoted drop beam, a pulley thereon and under which one of said cables is trained, crank arms mounted on the shaft of one of said drums, an arched-shaped member supported by said arms and straddling said beam and adapted to intermittently engage the latter and lower the same to exert a pull on said cable, and clutches connecting said arms with the shaft, whereby the arms may be rendered inactive to hold the arched-shaped member immovable.

2. In a machine of the character described, a frame, shafts journaled thereon, drums loosely mounted on said shafts, clutch mechanism for independently controlling the rotation of said drums with said shafts, a pivoted drop beam, crank arms slidably mounted on the ends of one of said shafts, an arched-shaped member supported by said arms and straddling said beam, and adapted to intermittently engage and lower the beam, clutch collars mounted on said shaft, cooperating clutch members carried by the arms, and means for sliding the arms away from the clutch collars to render the arms and arched-shaped members inactive.

3. In a machine of the character described, a frame, shafts journaled thereon, drums loosely mounted on the shafts, clutch mechanism for independently controlling the rotation of the drums with said shafts, a pivoted drop beam, crank arms slidably mounted on the ends of one of said shafts, clutch collars fixed on said shaft, cooperating clutch members carried by the arms for engagement with said collars, a sleeve rotatably surrounding each collar, and cooperating means carried by the sleeve and the adjacent side of the frame, whereby the arms are separated from the collars upon movement of the sleeves in one direction to render the arched-shaped member inactive.

4. In a machine of the character de-

scribed, a frame, a shaft journaled thereon, a drum loosely mounted on the shaft, clutch mechanism connecting the drum and shaft, a cable adapted to be wound about and unwound from said drums, power operated means for rotating said shaft, manually operable means for rotating said shaft and including a gear fixed on said shaft, a shaft

mounted for sliding movement tangentially of said gear, means for rotating the last mentioned shaft, and a worm gear carried thereby and adapted to be moved into operative association with the aforementioned gear. 10

In testimony whereof I affix my signature.

JASPER EMET HIGDON
